IGNITION SYSTEM FOR GAS OR LIQUID
FUEL APPLIANCES

Birchard L. Matthews and Edward J. Zarybnicky,
Cleveland, Ohio, assignors to The W. J. Scheen-
berger Company, Cleveland, Ohio, a corporation
of Ohio

Application June 29, 1945, Serial No. 602,241

3 Claims. (Cl. 158—117.1)

1

This invention relates to safety control and ignition systems for gas or liquid fuel heating or cooking appliances employing a main burner.

It has been common practice to employ a pilot light or other ignition means, such as a hot wire or spark, for lighting the main burner of such appliances but much difficulty has been experienced with the safety controls employed with these pilots due to the adverse effect which ambient heat has had upon such prior controls.

One of the principal objects of the invention is to reduce the hazards encountered with prior safety pilot controls incident to current failure, fuel failure, or extinguishment of the pilot light.

Another object is to provide positive fuel shut-off in case of pilot extinguishment, which will not be interfered with by the heretofore troublesome factor of ambient heat.

It is a further object of the invention to provide for fuel shut-off to the main burner when the height of the pilot flame has decreased to such an extent that it does not give instant ignition, as in the case where delayed ignition results from the pilot orifice slowly closing off due to foreign matter in the fuel.

Still another object of the invention is to provide an automatic ignition system in which a time interval will occur between the lighting of the pilot and the ignition of the burner, thus assuring the person lighting the pilot sufficient time to perform this operation and remove his hand from the combustion chamber before fuel is allowed to flow to the main burner.

Other objects and advantages will be in part described and in part obvious as the description is considered in connection with the accompanying drawings, in which:

Figure 1 is a horizontal section view of the top portion of a gas range, equipped with the improved ignition system;

Figure 2 is a sectional view of the solenoid valve employed in the system;

Figure 3 is a sectional view of a modified form of ignition pilot which is relatively adjustable with respect to the light tube; and

Figure 4 is a diagrammatic view of the electric circuits employed in the system.

Having more particular reference to the drawing wherein, for the purpose of convenience, we have shown our improved ignition system applied to a range 1, having a burner 4 for which, in the embodiment of the invention herein shown, safe ignition is to be provided. However, it will be understood that the invention is applicable for use with all forms of heating and cooking equip-

ment wherein a heating or cooking burner is employed.

The range 1 comprises a burner section or compartment 2, housed within a casing 3 and containing the burner 4, which gets its ignition from a constant burning pilot 16, described more in detail hereinafter. A pipe 6 connected at one end to a gas manifold 7 and at its other end to the pilot 16, supplies gas to the latter, while the mixing tube 8 of burner 4 receives its supply from the manifold 7, through the medium of a fuel pipe or line 9. The inlet end of this line 9 is connected to the manifold 7. A thermostatically controlled valve 11 and an electrically controlled valve 12, both of conventional construction, are interposed in the fuel line 9, between the manually operated shut off valve 10 and the mixing tube 8. Valve 11, which is supported in the front wall 18, of the casing 3 and connected to a thermo-bulb 19, positioned within the burner section or compartment 2, automatically regulates the oven temperature without interfering with the valve 10 for manually turning the burner 4 on or off. Valve 11 could be readily replaced by an electric thermostat (not shown) that would operate the solenoid valve 12, in response to temperature changes in the oven chamber when the ignition system, about to be described, is functioning properly.

30 Electrically operated control valve 12, described more in detail hereinafter, automatically controls the flow of gas to the main burner but not to the pilot 16. A photo-electric tube 100 and housing 29 therefor is located outside the oven or combustion chamber 2, in the space 30 between the division walls 14, and a light tube 31, fixedly mounted in bracket 33, is positioned between the photo-tube 100 and the ignition pilot 16, for directing light from the pilot flame 32 of pilot 16, 40 to the photo-tube 100. In the event the pilot flame 32 decreases in height, beyond a predetermined safe height for positive ignition, the flame 32 will no longer appear across the opening at that end of the tube, as illustrated in Figure 1.

45 In Figure 3 I have disclosed a modified form of the invention wherein a pilot 16' is connected to a light tube 31', for relative movement with respect to each other, by means of a bracket 33'. One end of the bracket 33' is bolted to the free 50 end of the tube 31', and at its other end is adjustably confined between lock nuts 34 and 35 threadedly mounted upon the outlet end of the pilot 16', which projects loosely through the opening 25 in that end of the bracket 33'. This 55 enables the operator to accurately position the

restricted orifice 38 of light tube 31' with respect to the pilot flame, so that the moment the latter drops below the opening 38 the device will be shut off. Manual adjustment of the flame 32' is effected by screwing or unscrewing pin valve 17. In this connection it will be noted that the resilience of the pipe 8 on which the pilot is mounted is sufficient to permit slight movement of the pilot relatively to the light tube. Pilot 16' is identical with pilot 16 with the exception that it employs the lock nuts 34, 35 and is physically connected to the light tube.

Suitably secured to the back wall of range 1, remote from the combustion or oven chamber 2, as by bolts 21, is a housing 38, for containing an amplifying tube 39, relay 40 and transformer 41 which, together with the solenoid valve 12 and photo-tube 100, receives current from a 110 volt source of supply 43, through the medium of wiring about to be described. The operation of the system is as follows:

Assuming that the constant burning pilot 16, which receives gas direct from the manifold 7, has been ignited by hand, and that the valves 10 and 11 are in full open position, fuel will flow through the supply line 8, of the main burner 4, up to but not beyond the electric control valve 12. The pilot 16 burning in front of the light tube 31 actuates the photo-cell 100 which, in turn, allows current to be passed through the amplifier tube 39, thereby actuating the relay 40 which operates the electric control valve 12. This valve then assumes an open position, allowing fuel to be supplied to the main burner 4 which is ignited by the pilot 16.

Photo-cell 100 will continue allowing current to flow through the amplifying tube as long as the photo-cell 100 receives light from the ignition pilot 16. In the event pilot 16 is extinguished, light is no longer received by photo-cell 100, thereby preventing the amplifying tube 39 from supplying current to the relay 40, which assumes an open position and causes electric control valve 12 to shut off. When a thermostatically controlled valve, such as the valve 11, is also placed in the main fuel line, the system can continuously function in response to the temperature of the combustion chamber as long as pilot 16 is ignited.

In the event of fuel failure, there will be no light source 16 in front of the light tube 31 which prevents the electric control valve 12 from opening. If the valve 12 is in an open position at the time of fuel failure, it will immediately assume a closed position. Furthermore, in the event of electric power failure, the solenoid valve 12 will also close. If the appliance had been in operation at the time of power failure, it will automatically resume operation when the current supply is resumed. In this case, the pilot 16 has either continued to burn or can be ignited. Upon resumption of the power, therefore, the pilot 16 will at once actuate the photo-tube 100 and thereby automatically effect ignition of the main burner 4. It will be understood that when the electric power is on the coil 44 of electric valve 12 will be energized thus causing the plunger 45 to be lifted from its seat 46, against the tension of spring 42, to place the inlet opening 47 in communication with outlet opening 48.

Having reference to Figure 4, it will be noted that the diagram there shown consists of a photo-tube 100 controlling the current flow through amplifying tube 39. The amplifying tube 39 operates the relay 40 which, in turn, controls the

operation of the solenoid valve 12. The photo-tube 100 is a two-element tube having a cathode 49 and an anode 50. The amplifying tube 39 has an anode 51, commonly known as the plate of the tube, a cathode 52, and a grid 53.

In the circuit shown, the three-step 110 volt A. C. transformer 41 is used to supply the proper voltage to the various parts in the circuit. A voltage of approximately six volts is taken from the transformer between the points 54 and 55 to supply current for cathode heating. The proper voltage for the plate circuit is taken from the transformer 41 between the connections 56 and 54. The voltage required for the grid circuit is taken from the transformer between the points 55 and 57. A resistance 58 and a condenser 59 are connected in the grid circuit as shown. The photo-tube 100 is connected across the grid 53 and the plate 51 of the amplifying tube 39. The photo-tube 100, as previously described, is connected so that it will pass current when a light source is directed on to it.

The photo-tube 100 illustrated is an emissive type of tube such as the PJ-23 or 930 put out by the General Electric Company. The amplifying tube 39 is a common low power radio receiving type of tube. It is not the intent of this descriptive material, however, to limit the device to these particular types of tubes.

In the device shown, which includes a common type of amplifying circuit, the photo-tube 100 will not pass current unless it is receiving a beam of light. The amplifying tube 39 will not pass current except under proper conditions of negative charge on the grid 53. Using this type of amplifying tube, a negative charge or bias is maintained on the grid 53 to prevent current flow across the plate circuit from cathode 52 to plate 51 until such time as the current flow is desired. The resistance 58 is included in the circuit to obtain the desired negative charge on the grid 53. The purpose of the grid condenser 59 is to decrease the grid bias required to reduce the plate current to a given value when the photo-cell is dark. The negative grid voltage is out of phase with the plate voltage when high values of grid resistance are used, thus making ineffective the grid control. This is due to the input capacity of the tube in combination with the grid resistance. The condenser 59 brings more nearly in phase the effective grid bias and the plate voltage.

The primary coil 60 of the transformer 41 is connected to the domestic voltage supply. When the system is put into use, therefore, current flows from the secondary coil 61 at 57 through wire 62, grid resistance 58 and wires 63 and 64 to condenser 59 and will continue to flow until the latter is charged. After the condenser charge has reached equilibrium, there is no voltage drop in the grid circuit as long as the photo-tube is dark, as there is no flow of current from the grid 53 of the amplifying tube 39. Since the grid 53 is connected to the resistor 58 and condenser 59 thru wire 65 a negative bias or charge is maintained on the grid 53 of sufficient magnitude to prevent electrons flowing from the cathode 52 to plate 51 of tube 39. It will also be seen that current at the same time flows from the low voltage point 55 thru wire 66, cathode heater 52 and returns by wire 67 to transformer 41 at point 54 and brings the cathode 52 up to the required temperature for operating the amplifying tube 39. The very low resistance type relay 40 is installed in the plate circuit between the plate 51 and the transformer connection 56. To operate this relay,

It is necessary to have a current flow in the plate circuit of the amplifying tube 39.

By igniting the constant-burning pilot light 16, a source of light is directed on to photo-tube 100. Electrons will then flow from wire 65 thru wire 68 to cathode 49, across vacuum tube 100 to anode 50 and thence thru wires 69 and 70, the coil of relay 40, and wire 71 to transformer tap 56. The low current from the photo-tube passing through the coil of the relay is not of sufficient strength to cause the relay to close contacts 73 and 74. This flow of current thru the photo tube 100 lessens or decreases the negative bias that has been maintained on grid 53 which immediately allows electrons to flow thru the amplifying tube 39 from the cathode 52 to the node or plate 51. The plate circuit then has current flowing from the transformer tap 55 thru conductor 66, amplifying tube 39, fuse 12, relay 40, and back to transformer connection 56. This current flow will actuate relay 40 so as to "make" contacts 73 and 74. Current will then flow from the volt source 43 thru wire 75 contacts 74 and 73, wire 77 thru coil 44 of solenoid valve 12 and thence back thru wire 76 to said source 43. The coil 44 will then be energized, magnetically raising valve plunger 45 against the pressure of spring 42, thus opening passageway 46 of valve 12 and permitting fuel to flow to main burner.

When the photo-tube 100 is illuminated, it acts as a resistance in the circuit, and when passing current through the photo-tube to reduce the negative bias on the grid 53, a delay in the reduction of negative bias is caused until the condenser discharges. It is seen, therefore, that there is a time factor directly related to the resistance flow of the photo-tube and the size of the grid condenser, delaying the action of the amplifying tube 39 and the actuation of the relay 40. This delay time factor is a product of the resistance of the photo-tube in megohms and the condenser value in microfarads. By using the proper size condenser, it is possible to get a relay action on the operation of the relay of from a few seconds to as long as four or five minutes. It is apparent that, without a time delay on the starting of the cycle, the device would operate so quick that gas would be allowed to flow to the main burner the instant that a flame from a match was placed in front of the light tube when igniting the pilot. A delay in the starting cycle of sufficient time to allow the person to ignite the pilot and withdraw his hand from the combustion chamber is therefore highly desirable.

Extinguishment of constant-burning pilot 16 instantly stops of the flow of electrons between the cathode 49 and the anode 50 of the photo-tube. The negative bias on grid 53 of the amplifying tube 39 is immediately raised, and thereby instantly cuts off electron flow from the cathode 52 to the anode 51 of the amplifying tube, thereby causing relay 40 to open contacts 74 and 73 shutting off current flow to the solenoid valve 12, which then assumes a closed position, stopping the flow of gaseous fuel to the main burner. It is seen, therefore, that pilot extinguishment or fuel cut-off will instantly cause the ignition system to assume a safe condition by shutting off the flow of fuel to the burner. And, should the current fail, the relay 40, which is normally in an open position, immediately assumes this position.

In the event of failure of the life of the photo-tube no electrons will pass across its cathode 49 to its anode 50 and, as explained above, the negative bias on grid 53 is immediately raised, thereby

stopping flow of electrons from the cathode 52 to the anode 51 of the amplifying tube. It is seen, therefore, that in the event of failure of the life of the photo-tube 100 the system will operate to a safe condition, as no current will flow to the relay 40. Its contacts 73 and 74 will remain open and the electric control valve 12 will assume a closed position.

It is also apparent that, in the event of failure 10 of the life of the amplifying tube 39, there can be no current flow from the plate circuit of the tube which results in the relay assuming its open position and causing the solenoid valve 12 to close.

The fuse 72 is installed in the plate circuit as 15 shown. This is to make the system safe in the event of a short circuit of the photo-tube. If the photo-tube is short circuited, a heavier flow of current results in the plate circuit. A fuse, therefore, can be properly sized in the plate circuit to 20 blow if current in the circuit is raised above a predetermined value.

Having thus described our invention, what we claim is:

- 25 1. An ignition system for a gaseous or liquid fuel appliance comprising a fuel supply source, a main burner, a constant-burning pilot burner for said main burner, electrically operated main control valve for controlling the flow of fuel to said main burner from said source of supply, photo-electric cell responsive to the light from the pilot burner, a light tube positioned with respect to the constant burning pilot burner so that if the pilot decreases in height beyond a predetermined height light rays cannot be received by the photo-cell, actuating means responsive to said photo-cell for operating said electric main control valve, said means including a delay means to prevent the electric control valve from opening until a predetermined time interval has elapsed after lighting the pilot burner.
- 30 2. An ignition system comprising a fuel supply, a main burner, a constant-burning pilot burner, a photo-electric cell so located as to receive and be responsive to the steady source of light from the pilot burner, and means responsive to photo-cell for controlling the flow of fuel to the main burner said means including a delay means to prevent the said responsive means from opening until a predetermined time interval has elapsed after lighting the pilot.
- 35 3. An ignition system for gas and liquid fuel appliances having a fuel supply source, a main burner, a constant burning pilot burner, an electrically operated control valve controlling the flow of fuel to said main burner from said source of supply, a photo-electric cell located so as to receive and be responsive to the light from the pilot burner and actuating means responsive to the photo-cell for operating said electric main control valve, said means including a delay means to prevent the said responsive means from opening until a predetermined time interval has elapsed after lighting the pilot burner.
- 40
- 45
- 50

- 55 4. An ignition system for gas and liquid fuel appliances having a fuel supply source, a main burner, a constant burning pilot burner, an electrically operated control valve controlling the flow of fuel to said main burner from said source of supply, a photo-electric cell located so as to receive and be responsive to the light from the pilot burner and actuating means responsive to the photo-cell for operating said electric main control valve, said means including a delay means to prevent the said responsive means from opening until a predetermined time interval has elapsed after lighting the pilot burner.
